UNITED STATES PATENT OFFICE.

JOSEPH J. WALTON, OF NEW YORK, N. Y.

REFLECTOR.

SPECIFICATION forming part of Letters Patent No. 232,092, dated September 7, 1880.

Application filed January 26, 1880.

To all whom it may concern:

Be it known that I, JOSEPH J. WALTON, of New York, in the county of New York and State of New York, have invented certain new and useful Improvements in Reflectors; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

This invention relates to an improvement upon the reflectors shown in Patents Nos. 209,178 and 209,576; and it consists in the construction and arrangement of parts, as will be hereinafter more fully set forth.

In the annexed drawings, which fully illustrate my invention, Figure 1 is a rear elevation. Fig. 2 is a central vertical section. Fig. 3 is a detail view of my improved reflector.

A represents the reflector, which may be of conical, paraboloidal, hyperboloidal, or ellipsoidal form, provided with a slot, *a*, for the egress of the flame. One side of this reflector is provided with an opening, *b*, having on either side the ears *c*, formed and turned up from the body of the reflector. Said ears are provided with openings *d*, through which passes a rod, *e*, having at one end a screw-thread, *f*, to receive a nut, *i*.

B represents a collar so constructed that it will adapt itself to fit over either a candle or lamp-chimney, and having on one side a projection, *g*, provided with an opening, *h*, to receive the rod *e*.

C are sleeves through which the rod *e* passes. One end of each of these sleeves is beveled to bear against the collar, and the other end bears against an ear, *c*, and they prevent the ears being brought too close together, thereby getting the reflector out of shape.

By this arrangement it will be seen that while the advantages for reflecting the light at any angle are retained, the reflector may be thrown out of position without removing it from the light, as shown in Fig. 2, thereby producing a device that is easily and cheaply constructed and is perfect in its operation.

Having thus fully described my invention, what I claim as new, and desire to secure by Letters Patent, is—

The reflector A, having the slot *a*, opening *b*, and ears *c*, in combination with the collar B, rod *e*, nut *i*, and sleeves C, substantially as and for the purpose set forth.

In testimony that I claim the foregoing as my own I have hereto affixed my signature in presence of two witnesses.

JOSEPH J. WALTON.
